Primary Examiner — Susan Bennett Hattan*Assistant Examiner* — Marie D. Fast Horse*(74) Attorney, Agent, or Firm* — Widerman Malek, PL; Mark Malek(57) **CLAIM**

The ornamental design for an infrared communication apparatus, as shown and described.

DESCRIPTION

FIG. 1 is a front perspective view of an infrared communication apparatus according to the present invention.

FIG. 2 is a rear perspective view of the infrared communication apparatus illustrated in FIG. 1.

FIG. 3 is a front elevation view of the infrared communication apparatus illustrated in FIG. 1.

FIG. 4 is a rear elevation view of the infrared communication apparatus illustrated in FIG. 1.

FIG. 5 is a top plan view of the infrared communication apparatus illustrated in FIG. 1.

FIG. 6 is a bottom plan view of the infrared communication apparatus illustrated in FIG. 1; and,

FIG. 7 is a right side elevation view of the infrared communication apparatus illustrated in FIG. 1.

1 Claim, 7 Drawing Sheets(56)
